UNITED STATES PATENT OFFICE.

ISAAC MARKLEY, OF CLAY CITY, INDIANA.

HEATING-STOVE.

1,315,379.

Specification of Letters Patent. Patented Sept. 9, 1919.

Application filed May 1, 1918. Serial No. 231,864.

To all whom it may concern:

Be it known that ISAAC MARKLEY, a citizen of the United States, residing at Clay City, in the county of Clay and State of Indiana, has invented certain new and useful Improvements in Heating-Stoves, of which the following is a specification.

The invention relates to improvements in heating stoves.

10 The object of the present invention is to improve the construction of heating stoves and to provide a simple, practical and efficient device of comparatively inexpensive construction adapted to be arranged in the path of the products of combustion without interfering with the draft of the stove and capable of causing the said products of combustion on their way to the smoke-pipe to heat intensely air passing through the said 20 device.

A further object of the invention is to provide a device of this character capable of effecting a saving in fuel and of increasing the heating capacity of the stove and provided with means for directing the heated air downwardly and outwardly toward the floor for increasing the heating effect of the stove.

With these and other objects in view the invention consists in the novel construction, arrangement and combination of parts hereinafter fully described, illustrated in the accompanying drawing and pointed out in the claim hereto appended; it being understood that various changes in the form, size, proportion and minor details of construction within the scope of the claim may be resorted to without departing from the spirit or sacrificing any of the advantages of the invention.

40 In the drawing:

Figure 1 is a vertical sectional view of a heating stove constructed in accordance with this invention.

Fig. 2 is a horizontal sectional view, 45 through the upper portion of the stove on the line 2—2 of Fig. 1.

Fig. 3 is a horizontal sectional view taken substantially on the line 3—3 of Fig. 1.

Like numerals of reference designate corresponding parts in the several figures of the drawings.

In the drawing in which is illustrated the preferred embodiment of the invention the stove comprises in its construction an outer shell or casing 1 provided with a suitable base 2 and having a fire pot 3 adapted to con-

tain a grate 4 of the ordinary construction and to receive the fuel which is introduced in the stove at the front thereof. The stove is preferably provided at the front with a 60 door 5, but any other preferred form of door may be, of course, employed.

The shell or body is also provided at the top of the fire-box with an annular channel or passage 6 having perforations 7 interiorly of 65 the stove and provided at the front with an inlet 8 and suitable draft regulating means for controlling the passage of air into the channel. The introduction of air into the stove by means of the annular passage or 70 channel is adapted to increase the draft and to assist in supporting combustion.

Within the upper portion of the stove is arranged a downwardly tapered air heating device 9 constructed of cast metal or other 75 suitable material and terminating at its lower portion in a reduced rearwardly extending neck 10 preferably flanged at 11 and suitably secured to the shell or casing at the back thereof about an opening 12. 80 The opening 12 communicates with a cold air inlet passage or conduit 13 mounted exteriorly of the shell or casing at the back thereof and extending downwardly from a point above the neck 10 to the base of the 85 stove the lower portion being inclined adjacent the fuel pot 3 to conform to the shape thereof, the fire pot forming an inner wall for said inclined portion and adapted to take the cold air from the floor or lower 90 portion of a room and cause such air to pass upwardly into the heating device 9. The heating device 9 is intensely heated by the smoke and other products of combustion which pass upwardly to a smoke-pipe opening or outlet 14 to which an ordinary smoke-pipe is attached in the usual manner. The heating device is provided at its top with an outwardly extending substantially annular flange 15 which rests upon and is supported by the upper edge of the shell or casing of the stove, the flange 15 being suitably secured to the shell or casing to provide a tight joint to prevent the escape of the smoke and other products of combustion. 105

The heating device is equipped with a cover 16 supported by legs 17 in spaced relation with the flange 15 to provide an open space or outlet for the escape of the air heated by the device 9. The legs 17 rest upon the 110 flange and are supported by the shell or casing and may be secured to the same in

any desired manner and the said cover 16 which constitutes the top wall of the heating device is provided at its periphery with a downwardly extending curved flange 18 forming a hood or deflector and adapted to direct the heated air downwardly and outwardly toward the floor of a room and thereby prevent such heated air from passing directly upward from the stove to the 10 top of a room. The top wall or cover may be provided with a flanged opening for enabling a hot air pipe to be connected with the heating device for heating an upper room or rooms and the stove may also be 15 provided with an ornamental top if desired.

The cover of the stove is provided with an upper substantially concavo-convex section 16^a which is adapted to be swung to one side for exposing the cover to present a flat upper 20 surface in order that a receptacle may be placed upon the cover for heating the contents of the receptacle or utensil.

It will be seen that the heating stove is simple and comparatively inexpensive in 25 construction, that it is adapted to take the cold air from the floor or bottom of a room and subject it to the heating action of the products of combustion before the same pass into the smokepipe or flue and without interfering with the draft of the stove and 30 that the heating effect of the stove is increased by discharging such heated air in a downwardly direction. It will also be clear that the draft of the stove may be increased 35 or accelerated by the annular passage or

channel surrounding the top of the fire-box and that as a maximum heating effect is obtained from the stove, the consumption of fuel is reduced to a minimum and saving of the fuel is thereby effected.

What is claimed is:—

A heating stove including a shell and a heating device comprising a downwardly extending air heating member adapted to seat upon the upper edge of said shell, said downwardly extending member being mounted within the upper portion of the shell and provided at its lower end with a reduced portion or neck, an exterior cold air conduit mounted upon the shell or casing and communicating at the upper end with the reduced portion or neck and extending to the lower portion of the shell, and provided thereat with an inlet; and a top wall extending over the shell, legs depending from the wall and mounted upon the upper portion of said downwardly extending member and retaining said top wall and shell in spaced relation to form a narrow outlet for the heated air, said top wall being provided with a marginal flange extending downwardly to substantially the plane of the top of the downwardly extending member within the shell to conceal the space between the upper end of the downwardly extending member and the top wall and to deflect the heated air downwardly.

In testimony whereof I affix my signature.

ISAAC MARKLEY.
